T. L. TETIRICK AND P. J. MUELLER,
SHOE FASTENER.
APPLICATION FILED OCT. 4, 1920.

1,381,764.

Patented June 14, 1921.

UNITED STATES PATENT OFFICE.

TEDDY L. TETIRICK AND PHILIP J. MUELLER, OF JOPLIN, MISSOURI.

SHOE-FASTENER.

1,381,764.

Specification of Letters Patent. Patented June 14, 1921.

Application filed October 4, 1920. Serial No. 414,623.

To all whom it may concern:

Be it known that we, TEDDY L. TETIRICK and PHILIP J. MUELLER, citizens of the United States, residing at Joplin, in the county of Jasper and State of Missouri, have invented certain new and useful Improvements in Shoe-Fasteners, of which the following is a specification.

This invention relates to shoe fasteners, 10 and it comprises the combination with a shoe having an opening arranged in the front and a flap disposed in one side of the opening and adapted to overlap the other section of the shoe upper when in closed position, 15 of a fastener comprising a plate adapted to be secured to the shoe upper near the opening, a complementary fastening member hinged thereto and secured to the free end of said flap, and a wire reinforcing frame 20 secured to each end of said complementary member and forming a support for said flap.

In the present invention, we have provided a fastening device for shoes to be used 25 in place of the ordinary buttons and laces which may be instantly fastened and unfastened when the shoes are being put on and taken off.

The present invention is adapted to be 30 used in connection with a shoe having the usual opening and having a flap carried by one part of the shoe upper and adapted to overlap the other part when in closed position.

35 The fastening element comprises a pair of hinged complementary members provided with latching means whereby the members are locked together when in closed position. One of said members is secured to the shoe 40 upper and the other member is hinged thereto and connected to the end of the flap. The device is provided with reinforcing means consisting of a piece of wire adapted to extend along the edge of the opening to form 45 the hinge and along the edge for reinforcing purposes. This reinforcing member may be advantageously made in sections whereby it may be applied to low shoes, to the regulation height man's shoe, or to the high 50 boot worn by women.

When the fastening device is employed and the shoe is closed, it is entirely covered by the flap and is invisible, presenting a neat and attractive appearance.

55 In the accompanying drawings, we have

shown one embodiment of our invention. In this showing,

Figure 1 is a perspective view of a shoe showing the fastener applied and showing the flap closed. 60

Fig. 2 is a top plan view showing the flap in open position.

Fig. 3 is a front elevation of the fastener, and 65

Fig. 4 is a top plan view thereof.

Referring to the drawings, the letter A designates generally a shoe having an upper 1.

The upper is provided with the usual opening arranged in the front and a flap 2 is secured to the upper at one side of the opening. 70

As shown, the flap is arranged on the inside of the opening and is adapted to overlap the outside portion 3 of the upper when in closed position. Our improved fastener comprises a pair of complementary 75

members 4 and 5. The member 4 is secured to the portion 3 of the upper in any suitable manner as by staples 6 formed integral therewith. It is provided with a lip or catch 7 adapted to coöperate with fastening means 80

carried by the complementary member. Suitable reinforcing means are secured to the edge of the portion 3 and the edge of the flap. 85

As the flap is substantially V-shaped, the reinforcing means at the bottom consists of a substantially V-shaped wire member having arms 8 and 9. These arms may be provided with loops 10 whereby the reinforcing member may be sewed to the shoe. 90

Referring to Fig. 3 of the drawings, the reinforcing member is made in sections whereby the fastener may be employed with shoes of different heights. When used with 95

a low shoe, the lower V-shaped member is employed and one fastening device is used 100 therewith. When the device is to be employed in connection with men's high shoes, an upper section of the reinforcing device is employed. As shown, this section com-

prises arms 11 and 12 adapted to be arranged on the edge of the flap and the edge of the upper respectively, the two arms being connected at the top and bottom by cross members 13 and 14. This member may also 105

be provided with loops 15 whereby it is secured to the shoe. A substantially rectangular portion comprising arms 16 and 17 and connecting members 18 and 19 may be used when the fastener is attached to ladies' high

shoes. 110

One of the arms of the reinforcing member is adapted to form a pivot for the pivoted member 5 of the fastening device. As shown, the end of the stationary member 4 is forked as at 20 and the end of the pivoted member is provided with an enlargement 21. The forked end of the stationary member and the enlargement are provided with openings adapted to be arranged in alinement for the passage of the arm of the reinforcing member. The outer end of the reinforcing member is provided with an enlargement 22 having an opening therein for the reception of the outer arm of the reinforcing member. As shown, the pivoted member is provided with an offset 23 adapted to coact with the lip 7 of the stationary member to fasten the shoe in position.

In the use of our invention, the framework or reinforcing member is securely stitched to the flap and the shoe fitted to the foot of the wearer. The other arm of the reinforcing member is then secured to the lap 3 of the shoe and the stationary fastening member 4 is stapled to the shoe. The device may be adjusted toward or away from the edge of the upper to fit the shoe to the foot of the wearer. As shown in the drawings, the inner arm of the reinforcing frame work forming the pivot for the latching member is arranged to the edge of the lap. To make the upper of the shoe smaller, this pivot is adjusted outwardly away from the edge whereby more of the upper is overlapped and a smaller size is obtained when the fastener is closed. It will be apparent that this adjustment feature is very important and enables a shoe to be fitted to the foot of the wearer whereby a smooth and attractive upper is obtained. After the device has been secured in position, the shoe may be closed by arranging the flap 2 in the position shown in Fig. 1 and by placing the lip 7 and the offset 23 into position. To re-

move the shoe from the foot, the flap is 45 opened to the position shown in Fig. 2 of the drawings by grasping the edge of the flap and applying sufficient pressure to release the fastening member.

It is to be understood that while we have 50 described the preferred embodiment of our invention, various changes in the shape, size, and arrangement of parts may be resorted to without departing from the spirit of the invention or the scope of the subjoined 55 claims.

Having thus described our invention, we claim:

1. The combination with a shoe having a flap adapted to overlap the body portion 60 when in closed position, of fastening means comprising a member secured to the body portion of the shoe, a pivoted member connected to said first member and connected to the edge of said flap, and a wire reinforcing member having one arm extending 65 along the edge of said flap, and a second arm secured to the body portion of the shoe.

2. The combination with a shoe having a flap adapted to overlap the body portion 70 when in closed position, of fastening means comprising a member secured to the body portion of the shoe, a pivoted member connected to said first member and connected to the edge of said flap, and a wire reinforcing member having one arm extending along 75 the edge of said flap, and a second arm secured to the body portion of the shoe, said second arm forming the pivot for said pivoted member.

In testimony whereof we affix our signatures in presence of two witnesses.

TEDDY L. TETIRICK.
PHILIP J. MUELLER.
